PROTECTIVE ROLLING SCREEN FOR
WINDOWS, DOORS, AND THE LIKE

Adolf Himmelmann, Dortmund, Germany

Application June 23, 1930, Serial No. 463,209
In Germany June 25, 1929

3 Claims. (Cl. 189—56)

The present invention relates to a rolling screen as a protection for doors, windows and the like which is provided with a safety mechanism to prevent the screen from being lifted up 5 from the outside by unauthorized persons. The advantages of the new rolling screen consist above all things in the possibility of its being rolled up with ease, combined with a small winding radius, and in the connection of the individual parts of 10 the screen being protected against manipulation from the outside, provision being, however, made for allowing a clear view and a ready passage of light through the screen.

The new rolling screen consists essentially of 15 horizontally disposed cross beams and corrugated bars which are arranged zigzag fashion and serve for supporting the beams and filling the openings, whereby the cross beams and corrugated bars are flexibly connected by special connecting members. In accordance with the invention, the rolling screen is additionally provided with a safety mechanism which prevents the screen from being raised from the outside by unauthorized persons. This is effected by spring pawls which are secured 20 to the cross beams or corrugated bars and connected with members fastened to the winding drum. The pawls engage with notches on the fixed guide of the screen or frame when the screen is unfolded. The pawls are lifted out of 25 the notches, when the screen is being rolled up, by means of tension members.

In accordance with the invention, the connecting members not only vary with regard to their shape, but also in the manner in which they are 30 connected with the cross beams and corrugated bars, flexibility of the connections being, however, ensured.

A variety of constructions of the new rolling screen with the safety mechanism is shown in 35 the accompanying drawings, in which—

Fig. 1 is a side view showing the rolling screen with the safety mechanism suspended from a rotatable drum.

Fig. 2 is a front elevation, Fig. 2a, a cross section and Fig. 2b, a plan view showing the construction of the flexible connection between two corrugated bars and a cross beam.

Fig. 3 is a side elevation of a modified construction of the flexible connection between the corrugated bars and cross beams.

Fig. 4 shows another modified construction of the flexible connection between two corrugated bars.

Fig. 5 is a front elevation and Fig. 5a, a sec-

tion of a further modified construction of the flexible connection between the cross bars,

Fig. 6 is a front elevation of a rolling screen showing a variety of shapes of the corrugated bars with and without cross bars which may be provided on the same screen.

Figs. 7 and 7a are perspective views of connecting members for cross beams and corrugated bars,

Fig. 8 is a section on line 10—10 of Fig. 6 through a flat-iron member serving as a connecting member with a pressed out distance piece,

Fig. 9 is a section on line 11—11 of Fig. 6 of a modified construction of a flexible connection of the corrugated bars,

Fig. 10 is a front elevation of a screen consisting of cross bars and corrugated bars, the cross beams and connecting members being executed in various designs on the same screen, and

Fig. 11 is a section through Fig. 10 on the line 11—11.

The rolling screen according to Fig. 1 consists of horizontally disposed cross bars or cross beams 1 of flat-iron. Corrugated bars 2, likewise made 25 of flat-iron and formed into a zigzag shape, are provided between two such cross beams and serve for supporting the cross beams and for filling the opening. These cross beams are flexibly connected together by a flat-iron member 3. A flat-iron 30 set on edge in respect of the plane of the screen may be interposed as a second cross beam 1'.

The rolling screen formed in this manner is suspended from discs by means of bolts and link members 4 so as to be adjustable, these discs being fastened to the drum 6. A tension member 7, e. g., a chain, is secured to the disc and provided with a tightening device 7' and a yieldable member 7''. The free end of the tension member is connected with a pawl 8 arranged on the inner side of the rolling screen. The pawl is under the action of a spring 8' which allows it to drop into a notch 9 of the frame 9' the moment both parts register in the bottom position of the rolling screen. In this manner connection is established between the screen in the unfolded position and the fixed casing of the screen which makes it impossible for the screen to be raised, for instance, from the outside by unauthorized persons. However, if the drum 6, which is not 40 accessible from the outside, is revolved, the screen is in the first instance drawn forward from the position in which it is suspended from the drum with a little play, but without lifting it, and the pawls 8 pulled out of the notches 9 during this 45

short space of time by the immediately tightened tension members 7 so that the screen is now released from the fixed frame 9' and may be rolled up.

5 The corrugated bars 2 forming the rolling screen, and also the cross beams 1', are provided with perforations for inserting the flat-iron member 3 serving for the flexible connection, as shown in Fig. 2. Two holes 10 are punched which are 10 connected by a narrow slot so that two lugs 11 are left standing between the holes 10. To allow the connecting flat-iron member to be inserted, these lugs are bent outwardly in the direction of the arrows *x* and then bent back again in the direction 15 of the arrows *y* into a square aperture 13 in the inserted flat-iron member. In this manner the flat-iron member is rigidly connected with the cross beam so that no shifting can occur. This flat-iron member 3 may be provided at the ends 20 with punched lugs or tongues 3' which, by acting as limiting stops, prevent the cross beams from falling out of the corrugated bars. They are provided with square projections 3'' on both longitudinal sides which serve as distance pieces and 25 abutments. According to Fig. 2a, the corrugated bars are fitted at specific points with elongated perforations through which the flat-iron member 3, which serves as a connecting member, is passed with a certain amount of play so that two corrugated bars and one cross beam are clamped together. After passing the flat-iron 3 through 30 the elongated perforations, the flat-iron member is bent over at the ends, thus forming the flexible connection between the bars and beams. The punched tongues 3' do not follow the bending 35 action, but remain square so that they act as stops and prevent the flat-iron members from dropping out of the perforations of the corrugated bars. In case the cross beam 1'' is formed as a 40 flat-iron member set on edge, as shown in Fig. 3, the flat-iron member, which in other respects is formed as described in the foregoing, is riveted to the cross beam 1, while the bent ends engage with perforations in the corrugated bars. Fig. 45 4 shows another construction in which the punched tongues 3' are dispensed with and the end 3''' of the flat-iron member is bent over twice outside the perforation in the corrugated bar, whereby security is afforded against the member slipping out of the perforations.

50 According to Fig. 5, the ends of the connecting flat-iron member 3 are joggled above the corrugated bars, mandrels or rivets 12 being inserted in the joggled portion which project in the joggling direction.

Fig. 6 shows a rolling screen in which the cross beams and corrugated bars are not only connected in various ways as described above, but in which the corrugated bars no longer have a straight-line zigzag form, but rather a zigzag shape composed of curves and straight lines.

60 According to Fig. 6, the corrugated bars and cross beams are connected in the upper portion of the rolling screen by a two-piece flexible member as shown in Figs. 7 and 7a. One of the flexible members 17 fits into the other flexible member 17', both being U-shaped. A mandrel or rib 14 is provided on the web of the U-section, the rib being passed through a corresponding perforation 70 in the cross beam or corrugated bar and connected therewith by welding or riveting. The flanges of these flexible members are fitted with perforations 15 which may be arranged either concentrically or eccentrically. After fitting the 75 flexible members together, a bolt 16 is passed

through the projecting ends and countersunk to form rivet heads, or a hollow bolt may be inserted and the rims expanded or beaded over, not shown. The corners of the flanges of the flexible members are rounded off on one side so that the other edges, which remain square, may support each other and thus prevent the rolling screen from sagging and bulging outwards in its vertical plane. Each flexible member is preferably formed of a T-section, the web of which is cut away to the required width for the rib 14. The flanged ends are provided with perforations and bent square at the requisite distance apart.

5 In Fig. 8 on the line 10—10 of Fig. 6, and in Fig. 9 on the line 11—11 of Fig. 6 are shown other 15 constructions of the flexible connections which are especially adapted for connecting corrugated bars. This again concerns the previously described flat-iron member 3 which is furnished with square projections as distance pieces on 20 both longitudinal sides. The ends of the inserted flat-iron member projecting from the perforations of the corrugated bars are bent outwardly in one operation and tongues 3' punched out in the direction oppositely disposed to the 25 bending direction. As shown in Fig. 8, the operation of making the connection by means of a flat-iron member may be simplified by pressing out the middle portion 18 of the flat-iron member so that this pressed out portion serves as a 30 distance piece between the corrugated bars.

35 Figs. 10 and 11 show a fifth construction of the connecting members for a rolling screen consisting of cross beams and corrugated bars. As the connecting members hereby used are made 40 in such a manner that they serve at the same time as supporting members, the flat-iron corrugated bars may in this case likewise be dispensed with.

45 The member serving as flexible connection is here formed by a vertically disposed bar 19 of T-section. The notched ends of the bars are passed through corresponding perforations in the cross beams and corrugated bars and folded into eyes 19'. Short lengths of 50 tubing 20 are passed through these eyes to act as connecting media, the tubes being beaded over at the ends to prevent them from dropping out. A through bar 21 of round-iron may, however, be used in place of the tubing, and in this case the bar 21 may profitably be bent to a 55 zigzag form similar to a corrugated bar, thus dispensing with a separate flat-iron corrugated bar, and at the same time reducing the number of cross beams. These supporting connecting bars 19 are bent outwardly at their middle portion 19'' to allow the diameter of the rolled screen to be kept as small as possible.

60 In addition, the cross beams 1 of flat-iron may be fitted at their outside edges with a covering bar arranged square to the beam in the plane of the screen, the construction being such that with two adjacent cross beams one of the bars reaches over the other, thus covering the flexible connection and safeguarding it from external 65 manipulations.

Fig. 6 shows a rolling screen constructed only of flexibly connected corrugated bars, the horizontal cross beams of the middle portion being dispensed with. The fields formed by these flat-iron bars are filled by two steel wires 22 which are passed through the corrugated bars to form two oppositely disposed diagonals. By adopting 70 this method of construction, the advantage is above all things gained that less material is re- 75

quired, ample flexibility and greater security being ensured by the open spaces in the fields being more closely filled.

What I claim is:—

- 5 1. A rolling screen for windows, doors, and the like, comprising a plurality of partly rectilinear grid-like cross members extending parallel to the rolling axis, a plurality of jointed connecting members extending at right angles to the cross members, and a plurality of links, a number of said cross members consisting of flat bars which are disposed edgewise to the plane of the screen and jointed to each other by said links in such a manner that the ends of the links pass through
- 10 corresponding openings in the flat bars of the cross members and are offset.
2. A rolling screen according to claim 1, in which a flat bar is bent to a zigzag or wave form and is associated at both longitudinal sides with rectilinear flat bars to form a reinforced structure, and the rectilinear bars being connected by the links with a bent bar at the reversal places of the zigzag portions.
3. A rolling screen according to claim 1, in 10 which the links are offset at their projecting ends and are provided with rivet heads or lugs for limiting the joint movement of the bars.

ADOLF HIMMELMANN.
